(57) **CLAIM**

I claim the toy guitar with expandable neck, as shown and described.

DESCRIPTION

FIG. 1 is a top isometric view of a toy guitar with expandable neck in a first configuration.

FIG. 2 is a bottom isometric view of the toy guitar with expandable neck of FIG. 1.

FIG. 3 is a front plan view of the toy guitar with expandable neck of FIG. 1.

FIG. 4 is a rear plan view of the toy guitar with expandable neck of FIG. 1.

FIG. 5 is a bottom elevation view of the toy guitar with expandable neck of FIG. 1.

FIG. 6 is a top elevation view of the toy guitar with expandable neck of FIG. 1.

FIG. 7 is a right side elevation view of the toy guitar with expandable neck of FIG. 1.

FIG. 8 is a left side elevation view of the toy guitar with expandable neck of FIG. 1.

FIG. 9 is a top isometric view of the toy guitar with expandable neck in a second configuration.

FIG. 10 is a bottom isometric view of the toy guitar with expandable neck of FIG. 9.

FIG. 11 is a front plan view of the toy guitar with expandable neck of FIG. 9.

FIG. 12 is a rear plan view of the toy guitar with expandable neck of FIG. 9.

FIG. 13 is a bottom elevation view of the toy guitar with expandable neck of FIG. 9.

FIG. 14 is a top elevation view of the toy guitar with expandable neck of FIG. 9.

FIG. 15 is a right side elevation view of the toy guitar with expandable neck of FIG. 9.

FIG. 16 is a left side elevation view of the toy guitar with expandable neck of FIG. 9; and,

FIG. 17 is a top isometric view of the toy guitar with expandable neck in a third configuration.

(Continued)

The dashed lines in FIGS. 1-17 illustrate portions of the toy guitar with expandable neck that form no part of the claimed design.

1 Claim, 13 Drawing Sheets
